UNITED STATES PATENT OFFICE.

REINHOLD H. WAPPLER, OF YONKERS, NEW YORK.

SURGICAL INSTRUMENT.

Application filed October 16, 1924. Serial No. 743,856.

My invention relates to surgical instruments of the type in which an operating device such as a pair of forceps is connected, detachably or otherwise, with an optical instrument such as a cystoscope or an endoscope and usually embodying a small instrument known in this art as a telescope, all for the purposes of enabling the surgeon to look closely into various cavities, channels and ducts of the human body, and to remove therefrom foreign substances such as gall stones, missiles and superfluous growths.

More particularly stated, my invention comprehends a surgical instrument of the general character just mentioned, and provided with a pair of jaws and with an endoscope, these parts being each adapted relatively to the other so that, with the instrument as a unit inserted into a cavity of the body, the jaws of the forceps being open and the operator making his observations through the endoscope, his field of vision has the form of a cone extending out directly through the opening between the jaws, or in other words the jaws may be considered as a pair of shutters between which the operator looks out from the instrument, and thus the operator sees straight ahead of the open jaws.

My invention further contemplates the employment, in an instrument of this general character, of jaws curved or bent and thus adapted to grasp objects located a little to one side from the front or distal end of the apparatus, in connection with an endoscope so arranged that its field of vision extends laterally and coincides as far as practicable with the opening between the jaws, as above stated. By this arrangement, notwithstanding the unfavorable position of the object to be seen through the endoscope and grasped by the jaws, the operator can still easily see it through the endoscope and readily grasp it between the jaws, and as a rule as soon as he can see it all he can grasp it by simply closing the jaws.

My invention further contemplates improved mechanism connected with the jaws of the forceps and with a pair of handles for actuating the same so as to enable the operator to shift said handles angularly around into an infinite number of different positions, thereby facilitating the convenience of the operator in manipulating the jaws while holding the handles in any of said positions, the jaws being also as a unit

movable angularly into an infinite number of different positions, independently of the positions of the handles.

My invention further comprehends various improvements in endoscopes and surgical forceps adapted for use therewith, and also improvements upon various combinations of these parts with others as incorporated in a surgical instrument.

Reference is made to the accompanying drawing forming a part of this specification and in which like reference characters indicate like parts throughout the several figures.

Figure 1 is a side elevation of one form of my improved surgical instrument, in which the forceps jaws are curved, the jaws being here shown as closed.

Figure 2 is a fragmentary longitudinal cross section through the mechanism shown in Figure 1.

Figure 3 is partly a side elevation and partly a longitudinal section of the mechanism shown in Figure 1, various movable parts being shown as they appear when the jaws are open.

Figure 4 is a section on the line 4—4 of Figure 2, looking in the direction indicated by the arrows.

Figure 5 is a fragmentary inverted plan showing another form of my device, in which the forceps jaws are straight, the jaws being here shown as closed.

Figure 6 is a side elevation of the mechanism appearing in Figure 5.

Figure 7 is a side elevation of the mechanism shown in Figures 5 and 6, but with the jaws open.

I will first describe the form of my device appearing in Figures 1 to 4 inclusive.

A barrel 8 has a general tubular form, and is provided with a portion 9 curved to form a jaw. Another jaw 10, also curved but separate from the barrel, is mounted thereupon by means of a pair of journal necks 11 which extend into a pair of sockets 12, serving as bearings, and shown more particularly in Figure 4. Thus while the jaw 9 is rigid relatively to the barrel 8 and preferably integral therewith, the jaw 10 is adapted to move relatively to the jaw 9. The jaw 10 carries a cross pin 13, extending through a slot 14, as indicated in Figure 4, and encircling this cross pin is an annular bearing 15, provided with an extending portion 16. This extending portion is by means of fastenings 17 secured upon an operating tube 18.

The operating tube is movable back and forth in the general direction of its own length, and is used for actuating the movable jaw 10.

5 Secured rigidly upon the operating tube 18 and thus movable therewith is an operating sleeve 18^a, which extends telescopically into an annular head 19 and also into the adjacent end portion of the barrel 8 which 10 is fitted into this annular head, as may be understood from Figure 2. The operating sleeve 18^a is provided with a slot 20^a. A screw 20 extends through the wall of the cylindrical head 19 and the adjacent portion 15 of the barrel, and into the slot 20^a, so as to act as a spline pin. By this arrangement the operating sleeve 18^a is rendered slideable in the direction of its length but is unable to turn upon its axis owing to the screw 20 fitting into the slot 20^a.

An annular head 21 is provided with an annular portion 23 of reduced diameter, the annular head 19 being similarly provided with an annular portion 22 of the same diameter as the portion 23. A swivel collar 24 encircles the two reduced portions 22 and 23, and abuts neatly against the adjacent body portions of the two heads 19 and 21.

The swivel collar 24 carries a handle 25 integral with it, this handle having a portion 26 formed into a finger link, as may be understood more particularly from Figure 1. Another handle 27, having a portion 28 formed into a finger link, is mounted upon 25 the swivel collar 24 by means of a journal pin 29, as shown more particularly in Figures 2 and 3.

The operating sleeve 18^a is provided with an annular bearing 30, and the handle 27 is provided with a ball portion 31 fitting neatly into the annular bearing 30. By this arrangement the handle 27 may be moved back and forth upon the journal pin 29 as a center, and when so moved it causes the operating sleeve 18^a, carrying the operating tube 18, to be thrust back and forth in the general direction of the length of the barrel 8.

Since the operating sleeve 18^a is unable to 50 turn because held by the screw 20 acting as a spline pin, and since the swivel collar 24 carrying the two handles 25 and 27 is free to turn, it follows that these handles can together be rotated around into any required 55 angular position. For this purpose the ball portion 31 of the handle 27 merely glides around in the annular bearing 30, and this is done without disturbing the position of the operating tube 18.

60 The operating sleeve 18^a, and the adjacent end portion of the operating sleeve 18 secured fixedly thereto as above described, are together provided with a spline slot 32, as indicated more particularly in Figure 2.

65 A screw 33 extends through a portion of

the annular head 21 and into this slot and thus serving as a spline pin. By this arrangement the annular head 21 is prevented from turning, and is maintained always in registry with the annular head 9.

70 A pair of connecting pins 34 and 35 extend tangentially into the swivel collar 24, and engage the respective reduced portions 23 and 22 of the annular heads 21 and 19. For this purpose the reduced portions 23 75 and 24 are provided respectively with annular bearings 34^a and 35^a, so arranged that the connecting pins extend through them tangentially as may be understood from Figures 1 and 2. By this arrangement the 80 swivel collar 24 serves as a coupling between the annular heads 19 and 21 and holds these heads spaced apart by a definite distance which never varies and yet the swivel collar and parts carried thereby can turn freely, 85 as above described. The connecting pin 34 is provided with a milled head 36 and the connecting pin 35 is similarly provided with a milled head 37. This is for the purpose of facilitating the removal, replacement and 90 adjustment of the connecting pins.

95 The barrel 8 carries a hand valve 38, and connected with the latter is a rubber pipe 39, for supplying water into the barrel 8. Similarly, a hand valve 40 is mounted upon the annular head 21 for facilitating the discharge of water. I provide the barrel 8 with a pair of educts 41 disposed adjacent the jaws 9 and 10, to facilitate the flow of 100 water from the barrel 8. When the instrument is inserted into any cavity of the body and water is admitted through the pipe 39 and hand valve 38 into the barrel 8, the water can usually make its escape quite freely between the jaws 9 and 10; but if 105 the jaws happen to be closed, or so disposed relatively to the adjacent tissues of the body that the water cannot readily make its escape, it can easily pass through the educts 41. After the water fulfills its mission, such 110 for instance as washing out the cavity, it flows backwardly through the operating tube 18, and thence out through the hand valve 40.

115 An endoscope 42 extends through the operating tube 18, and is approximately concentric to the same. This endoscope is of the kind described in my pending application filed June 25, 1923, Serial No. 647,439. It is provided with a prismoid 43 and a lens 44, the latter serving as a window, and so co-operating with prismoid that the operator's field of vision, outwardly from the lens 44, has the proximate form of a cone, the 120 axis of which is oblique relatively to the general longitudinal axis of the endoscope.

125 A miniature lamp 45 is carried upon the distal end of the endoscope, and projects out into the fixed jaw 9. The endoscope is provided with an enlarged tubular portion 47, 130

and with a wire 48, the latter being connected with the lamp 45 for energizing the same. The wire 48 is connected with a metallic collar 49, insulated from other portions and used for making electrical connections.

The endoscope contains lenses, a pair of which are shown at 50. These lenses, the parts 48 and 49, and the wire 48 and its connectors, are here shown conventionally, as constituting no essential parts of my present invention.

Detachably mounted upon the tubular portion 47 is an annular head 51, carrying a dowel pin 52. An annular head 53, encircling the tubular portion 47, is provided with a dowel hole 54 into which the dowel pin 52 fits detachably.

Engaging the annular head 52 is a coupling link 55, having a threaded engagement with the annular head 21. The annular head 53 carries dowel pins 56, which fits into dowel holes 57. A gasket 58, made preferably of rubber, encircles the tubular portion 47 and is located between the annular heads 21 and 53. By removing the coupling ring 55, the annular head 53 and gasket 58 can be removed.

Located upon opposite sides of the metallic ring 49 are a pair of rings 59 and 60 of insulating material, preferably hard rubber. An annular head 61 is carried by the tubular portion 47, and detachably connected with this annular head 61 is another annular head 62, carrying an indicator knob 63, used as hereinafter described.

Two lenses are shown at 64 and 65, the lens 65 serving as an eye piece.

The parts 51, 52, and various other parts to the right thereof according to Figure 2, serve collectively the purpose of a handle for the endoscope, and enable it to be withdrawn and replaced bodily and as a unit.

With the handle in such position that the dowel pin 52 fits into the dowel hole 54, as indicated in Figure 2, the indicator knob 63 always extends in the same plane as that in which the jaws 9 and 10 are curved. Therefore, by noting the position of the knob 63 the operator can determine the angular direction in which the jaws extend.

The operator's field of vision, when looking through the endoscope and out through the lens 44 at the distal end thereof, is practically in the form of a cone, with its apex in the lens 44 and its axis extending obliquely downward and to the left according to Figures 1 to 3 inclusive.

The parts are so proportioned and arranged that when the jaws 9 and 10 are wide open, as indicated in Figure 3, the operator's field of vision is at its maximum; or in other words, the base of the cone of vision coincides substantially with the opening between the jaws 9 and 10 according to Fig-

ure 3. Such being the case, the jaws are for this purpose analogous to a pair of shutters through which the operator cannot see when they are closed, and through which he can see to the extent that they may be opened. The result of this arrangement is that the operator sees in the same proximate direction in which the jaws extend. The optical effect is about the same as if the operator's eye were to occupy the position of the lens 44, and the axis of his field of vision were to extend thence obliquely downward to the left according to Figure 3, so that he could look out between the jaws.

It follows from this arrangement that with the instrument as a unit inserted into a cavity of the body and the operator looking through the endoscope, any object which he can see plainly is of necessity located directly in front of the jaws and between them, and thence in favorable position to be grasped by the jaws. It also follows practically as a matter of course that the operator, in order to grasp the object between the jaws, need do little or nothing except close the jaws. Either before or after closing the jaws the operator can determine the location of the object mentioned, at least relatively to the distal end of the instrument, by merely noting the position of the indicating knob 3, as above described.

If the cavity contains blood, mucous, dirt or other substance tending to obscure the operator's vision, he can wash out the objectionable material by the flow of water through the instrument as above described.

In the form of my device shown in Figures 5 to 7 inclusive the barrel appears at 66, and integral with it is a straight stationary jaw 57. Co-acting with this stationary jaw is a movable jaw 68, also straight. With this form of my device, or even with the other form already described, the water connections may be discarded if this be desired.

With either form of my device the two jaws, if polished internally, act to some extent as reflectors and thus increase the efficiency of the illumination. In the forms shown in Figures 1 to 4 inclusive, the form of jaw 9 is especially favorable for this purpose.

The operation of my device is as follows:

The various parts being constructed and assembled as shown in the drawing and above described, the instrument is ready for use.

The barrel 8 being thrust into a cavity of the body, the operator swings the handle 27 into the position indicated for it in Figure 3, thereby causing the jaw 10 to assume the position indicated for it in this figure. The operator now looks through the endoscope, and by aid of light from the lamp 45, can see as above described.

Having located an object to be removed,

and if need be having shifted the position of the instrument slightly in order to bring the jaws into a more favorable position, the operator actuates the handle 27 and thus 5 closes the jaws upon the object to be removed. This done, the operator now carefully removes the instrument from the cavity, and in so doing brings out the object now held between the jaws.

10 If for any reason the operator wishes to shift the general position of the two handles 27 and 25, he merely swings them around bodily for this purpose as above indicated, thereby turning the swivel collar 24 as described. There is no danger of displacing either of the handles relative to the other, and the handles as a pair can be effectively operated in any angular position into which they can thus be turned.

15 20 I do not limit myself to the precise mechanism here shown and described as variations may be made therein without departing from my invention, the scope of which is commensurate with my claims.

25 I claim:

1. In a surgical instrument the combination of a barrel, a pair of hollow jaws mounted upon one end of said barrel and arranged to open and shut, and by so doing to open 30 and close said end of said barrel, means controllable by the operator for actuating said jaws, and an optical instrument extending through said barrel and having a field of vision substantially in the form of a cone 35 outwardly between said jaws, in such direction that the axis of the cone coincides substantially with the plane of movement of the jaws.

40 2. In a surgical instrument the combination of a barrel, a pair of jaws mounted upon one end of said barrel, mechanism connected with said jaws and controllable by the operator for the purpose of causing said jaws to grip and in so doing to close said end of said 45 barrel, an endoscope separate from said barrel and extending lengthwise therethrough, said endoscope having a field of vision extending obliquely from the general axis of the endoscope, said field of vision being in 50 the form of a cone so located that its axis coincides substantially with the plane of relative movement of said jaws in closing.

55 3. In a surgical instrument the combination of a barrel, a pair of jaws mounted upon one end of said barrel, mechanism connected with said jaws and controllable by the operator for causing said jaws to grip and thus to close said end of said barrel, an endoscope extending lengthwise through said barrel 60 and having a field of vision extending obliquely outward from said open end thereof and between said jaws when open, said field of vision having the form of a cone with its axis entirely within the general plane in 65 which said jaws are to be closed.

4. In a surgical instrument of the character described the combination of a barrel of substantially tubular form, a jaw rigidly mounted upon said barrel and curved so as to extend sidewise therefrom, said jaw being hollow, another jaw journaled upon said barrel and also curved so as to extend sidewise therefrom, said second mentioned jaw being hollow and movable relatively to said first mentioned jaw, operating mechanism connected with said movable jaw and extending through said barrel for enabling the operator to actuate said movable jaw, and an endoscope extending through said barrel and having a field of vision in the form of a cone 75 with its axis oblique to the general longitudinal axis of said barrel, said endoscope being so positioned relatively to said barrel and to said jaws that said field of vision of said endoscope is bounded by said jaws when 80 open.

5. In a surgical instrument of the character described the combination of a barrel, a pair of jaws supported thereby and an endoscope extending axially through said barrel 90 and into proximity to said jaws, an operating tube connected with one of said jaws for actuating it relatively to the other jaw, said operating tube being concentric to said barrel and to said endoscope, and mechanism 95 connected with said operating tube for moving it bodily back and forth in order to actuate said movable jaw.

6. In a surgical instrument of the character described a barrel of substantially cylindrical form, a pair of jaws supported by said barrel, an operating tube extending through said barrel and connected with said jaws, said operating tube being movable in the direction of its length for causing said jaws 100 to open and close, an operating sleeve mounted upon said operating tube and having a portion serving as a bearing and provided with an annular groove, a slip collar encircling said operating sleeve, mechanism 105 coacting with said slip collar and connected with said operating sleeve for supporting said operating sleeve, a movable handle journaled upon said slip collar and provided with a portion extending into said annular groove, 110 so that when said handle is moved back and forth said slip collar communicates motion to said operating tube and causes one of said jaws to be actuated, and another handle mounted upon said slip collar and coacting 115 with said first mentioned handle.

7. In a surgical instrument of the character described the combination of a barrel, a pair of jaws supported by said barrel, an operating tube connected with one of said jaws and extending through said barrel for operating said jaw, an operating sleeve carried by said operating tube and provided with a bearing of annular form, a slip collar encircling said operating sleeve and revoluble 125 130

relatively thereto, a handle journaled upon said slip collar and provided with a portion engaging said bearing for causing movements of said handle to actuate said operating sleeve, and mechanism connected with said slip collar for supporting said operating sleeve.

8. In a surgical instrument the combination of a barrel of substantially cylindrical form, a pair of jaws supported by said barrel, an operating tube connected with said jaws for actuating said barrel, an annular head encircling said barrel and secured rigidly thereto, another annular head encircling said barrel and loose relatively thereto, an operating sleeve mounted rigidly upon said operating tube and having spline connections to said first mentioned annular head

and to said second mentioned annular head in order to prevent each annular head from turning relatively to the other or to said operating sleeve, a slip collar engaging said operating sleeve and portions of said annular heads, said slip collar being revolvable relatively to said operating sleeve and to said annular heads, and a pair of handles carried by said slip collar, one mounted upon said slip collar and other journaled upon said slip collar and movable relatively thereto, said last mentioned handle being connected with said operating sleeve and movable for the purpose of actuating the latter.

Signed at New York, in the county of and State of N. Y., this 14 day of October, 1924.

REINHOLD H. WAPPLER.
